UNITED STATES PATENT OFFICE.

JOHN D. RISTINE AND BENTON C. ROWELL, OF CHICAGO, ILLINOIS; NORTON H. BYAM, ADMINISTRATOR DE BONIS NON OF SAID BENTON C. ROWELL, DECEASED, AND SAID JOHN D. RISTINE, ASSIGNORS TO ANCHOR BRAKE SHOE & MANUFACTURING COMPANY, OF CHICAGO, ILLINOIS, A CORPORATION OF ILLINOIS.

PROCESS OF MAKING BRAKE-SHOES.

1,257,122.

Specification of Letters Patent. Patented Feb. 19, 1918.

Application filed February 14, 1912, Serial No. 677,496. Renewed June 1, 1917. Serial No. 172,282.

To all whom it may concern:

Be it known that we, JOHN D. RISTINE and BENTON C. ROWELL, citizens of the United States, and residents of Chicago, in 5 the State of Illinois, have invented certain new and useful Improvements in Processes of Making Brake-Shoes, of which the following is a specification.

Our present invention relates to processes 10 of casting brake shoes and more particularly brake shoes containing strengthening inserts, and has special reference, first, to the provision of an improved process for the manufacture of shoes of the character referred to whereby one or more strengthening 15 inserts are most firmly anchored in the body of the shoe, and, second, wherein such strengthening inserts are not only anchored in the body but may also be anchored to 20 to other reinforcements or inserts or vice versa.

The principal objects of our present invention are the provision of an improved and simplified process for the manufacture 25 of brake shoes, by the employment of which the reinforcement of the attaching lug of the shoe and of the body of the shoe respectively may be firmly anchored together, and anchored in the body of the shoe, whereby 30 such reinforcements and one or more wearing inserts disposed in the body of the shoe may be anchored together and in such body, and whereby the molding and casting of brake shoes may be materially simplified.

35 By the employment of our improved process we are enabled to produce, first: structures, adapted in the event of breakage, to restrain any portion of either the insert or the body from falling upon the track; and, 40 second: an improved reinforcement and anchorage of the attaching lug, thereby preventing the shoe from becoming disengaged from the brake head and falling upon the track in the event of fracture of the cast 45 metal portions of such attaching lug, or the insert from falling upon the track should it in any wise become disengaged from the body portion of the shoe; and gain certain further features of benefit and advantage in 50 the construction of brake shoes which are also disclosed and claimed in our co-pending application Serial No. 664,625, filed December 8, 1911.

In carrying out our improved process and attaining the results referred to we preferably employ certain apparatus and elements illustrated in the accompanying drawing, wherein—

Figure 1 is a longitudinal vertical sectional view illustrative of a mold employed in casting one form of insert used by us;

Fig. 2 is a longitudinal vertical sectional view illustrative of a mold employed in casting a complete brake shoe;

Fig. 3 is a longitudinal elevational view, 65 partly in vertical section, illustrative of a brake shoe produced by our improved process;

Fig. 4 is an assembled plan view of the strengthening inserts employed in the reinforcement of the body of the shoe and the attaching lug therefor;

Fig. 5 is a sectional view taken on the line V—V of Fig. 4; and

Fig. 6 is a perspective view of the lug reinforcement.

In producing a wear resisting insert 10 (Fig. 5) we may employ a mold 11, (Fig. 1) and for producing either plain reinforced shoes or those containing wear resisting inserts 10, we may employ a mold such as indicated at 12 (Fig. 2). It will thus be apparent that by the employment of the mold 11, when we desire to produce shoes containing a wearing insert, we are enabled rapidly 80 to produce, all connected together as a unitary insert ready for emplacement into the mold 12 preparatory for the casting of the body of the shoe, the reinforcement for the back, the lug, and the wearing insert. 85 As will be seen on viewing Fig. 3, we have here illustrated the result of the employment of our process in connection with the production of the Master Car Builders' standard railway car shoe, the shoe body portion 95 13 being preferably made of relatively soft metal such as gray cast iron, the member 14 serving not only as a back to reinforce and strengthen the body of the shoe, but also to anchor the inserts 10 and the reinforcement 100 strap 15 for the lug 15^a in place in the shoe body, said strap 15 being preferably made of steel or other tenacious ductile metal, and, when used the inserts 10, Figs. 2 and 5, being relatively hard metal such as white cast 105 iron.

Referring now more particularly to Figs. 4, 5 and 6, it will be observed that preparatory to casting the wear resisting insert 10 in the mold 11 (Fig. 1) or the shoe embracing such insert, or a plain reinforced shoe, by the use of said mold 12 (Fig. 2), we preferably employ for the insert 14 a piece of material of such a degree of pliancy or flexibility as will permit its being bent so as to present oppositely disposed sides 14', 14² and preferably having a certain degree of elasticity or resiliency to the end that it may hold the lug reinforcement 15 between the portions 14' and 14². In order to prevent any displacement of the lug 15 relatively to the strengthening insert 14 we preferably employ a member of channel shape in cross section and form the legs 16 of the lug reinforcement 15 with offset portions 17 adapted to make close contact with the oppositely disposed portions 14' and 14² of the member 14 as is clearly to be seen in Fig. 5.

To the end that when the legs 16 of the lug reinforcement 15 are first compressed and then inserted between the channel portions 14', 14², and by the close contact shown the lug reinforcement 15 is prevented from disengagement with the member 14, the piece of material from which the member 14 is formed should be so bent that the flanges 18', 18² face each other and while the portions 14' and 14² of such member 14 need not be integral, we find this construction the most expedient since it is the least expensive manner of forming the reinforcement, and most desirable for preventing any broken away portion of the shoe body 13 from disengagement therefrom, and a most convenient means for maintaining the relative position of the lug reinforcement 15 and the member 14 during the pouring of the insert 10 in the mold 11, or of a plain reinforced shoe or a reinforced shoe containing inserts, in the mold 12.

The lug reinforcement 15 having been positioned between the opposing faces 14' and 14² of the body reinforcing member 14 and positioned in the mold 11 as shown in Fig. 1 the reinforcements 10 may then be poured, locking the parts 14 and 15 in the relative position shown in Fig. 4 and securing the wearing inserts 10—10 and the parts 14 and 15 together as indicated in Fig. 5, and thereby anchoring them against relative movement, without the employment during the pouring of the shoe of any supporting pins or other extraneous supporting member whatsoever.

The structure thus produced by the use of the mold 11 may then be placed in the mold 12 (Fig. 2) and the body 13 cast thereabout locking the members 10, 13, 14 and 15 against any relative movement whatsoever and preventing any falling away of any portion of

the body 13 should the shoe be broken transversely, or dropping of the shoe as a whole should the cast lug 15^a become broken in service.

Having thus described our invention and illustrated its use, what we claim as new and desire to secure by Letters Patent is the following:

1. The process of making brake shoes which consists in forming a strengthening 75 insert having a plurality of substantially parallel resiliently connected portions, bringing an attaching lug into engagement with said portions, and pouring a cast element about said insert, whereby said insert 80 is embedded in said cast element and said lug is restrained from movement relatively thereto.

2. The process of making brake shoes which consists in forming a strengthening 85 insert having substantially parallel resiliently connected portions, emplacing an attaching lug between said sides and pouring a body about said insert, whereby said insert 90 is embedded in said body and said lug is attached thereto.

3. The process of making brake shoes which consists in forming a strengthening insert having substantially parallel resiliently connected portions, emplacing an attaching lug between said sides and pouring a body about said insert and lug, whereby said insert is embedded in said body, said lug is attached to said body and said lug is strengthened by an extension of the cast 100 metal of said body.

4. The process of making brake shoes which consists in forming a strengthening insert having substantially parallel sides with inwardly directed flanges elastically 105 connected at their ends, emplacing an attaching lug between said sides and pouring a body about said insert, whereby said insert is embedded in said body and said lug attached thereto.

5. The process of making brake shoes which consists in providing an inwardly flanged insert having substantially parallel sides elastically connected at their ends, 115 emplacing an attaching lug between said sides, and pouring a body about said insert and lug, whereby said insert is embedded in said body, said lug is attached to said body, and said lug is strengthened by extension of cast metal of said body.

6. The process of making brake shoes which consists in providing an inwardly flanged strengthening insert having substantially parallel sides, providing wearing blocks on said insert, emplacing an attaching lug between said flanged portions and casting a body about said wearing blocks and flanged portions, whereby they are embedded in said body and said lug is attached thereto.

7. The process of making brake shoes which consists in providing an inwardly flanged strengthening insert having substantially parallel sides, providing wearing blocks on said insert, emplacing an attaching lug between said flanged portions and casting a body about said insert, blocks and lug, whereby said insert and blocks are embedded in said body and said lug is strengthened by 10 extensions from the cast metal of said body.

8. The process of making brake shoes which consists in forming a strengthening insert having a plurality of substantially parallel flexibly connected portions, bringing an attaching lug into engagement with said portions, and pouring a cast element about said insert, whereby said insert is embedded in said cast element and said lug is restrained from movement relatively thereto. 15

9. The process of making brake shoes which consists in forming a strengthening insert having substantially parallel flexibly connected portions, emplacing an attaching lug between said sides and pouring a body about said insert, whereby said insert is embedded in said body and said lug is attached thereto. 20

10. The process of making brake shoes which consists in forming a strengthening insert having substantially parallel flexibly connected portions, emplacing an attaching lug between said sides and pouring a body about said insert and lug, whereby said insert is embedded in said body, said lug is attached to said body and said lug is strengthened by an extension of the cast metal of 25 said body.

11. The process of making brake shoes

which consists in forming a strengthening insert, then casting a wearing insert in engagement therewith, and finally casting a body in engagement with said strengthening insert and around said wearing insert except for the wearing face thereof, whereby a part of the surface of said body and a part 45 of the surface of said wearing insert are presented in alternation. 40

12. The process of making brake shoes which consists in forming a strengthening insert, emplacing an attaching lug thereupon, then casting a wearing insert in connection with said strengthening insert and finally casting a body about said lug and strengthening and wearing inserts, whereby said lug and several inserts have cast 50 engagement with said body and said lug is strengthened by the cast metal of said body. 55

13. The process of making brake shoes which consists in forming a strengthening insert, emplacing an attaching lug thereupon, then casting a wearing insert in connection with said strengthening insert and finally casting a body about said lug and strengthening and wearing inserts, whereby said lug and several inserts have cast 60 engagement with said body and said lug is engaged by the cast metal of said body. 65

In testimony whereof we have hereunto signed our names in the presence of the two subscribed witnesses.

JOHN D. RISTINE.
BENTON C. ROWELL.
